(No Model.)

F. CROSS.

BURGLAR ALARM.

No. 319,566.

Patented June 9, 1885.

FIG. 1.

FIG. 2.

FIG. 3.

FIG. 4.

UNITED STATES PATENT OFFICE.

FRANK CROSS, OF WASHINGTON, INDIANA.

BURGLAR-ALARM.

SPECIFICATION forming part of Letters Patent No. 319,566, dated June 9, 1885.

Application filed October 15, 1884. (No model.)

To all whom it may concern:

Be it known that I, FRANK CROSS, a citizen of the United States, residing at Washington, in the county of Daviess and State of Indiana, 5 have invented a new and useful Improvement in Burglar-Alarms, of which the following is a specification, reference being had to the accompanying drawings.

My invention relates to burglar-alarms; and 10 it consists in the construction and novel arrangement of parts, as will be hereinafter fully described, and particularly pointed out in the claims.

In the drawings, Figure 1 is a front elevation 15 of my improved burglar-alarm. Fig. 2 is a vertical section. Fig. 3 is a horizontal sectional view on the line $x-x$ in Fig. 1, and Fig. 4 is a detailed view thereof.

Referring by letter to the accompanying 20 drawings, A designates the alarm-case, which is provided with a door, B, having a window, C. Within the alarm-case A, I provide gearing consisting, preferably, of a drive-wheel, D, driven by a coil-spring, E. The drive-wheel 25 engages a pinion on a shaft, F, which latter shaft is also provided with a spur gear-wheel, G, which engages a pinion, H, on a shaft, H'. The shaft H' is also provided with an escape- 30 ment-wheel, I, which engages the lever I', pro- vided with the bell-hammer J. A small call- 35 bell, H², at the bottom of the alarm-case is pro- vided, upon which the hammer J strikes when the gearing is operated. Above the gearing 40 at the rear of the case A is a cross-strip, K, which forms a bearing for the rear ends of the 45 shafts L L', the front bearings of said shafts L L' being in blocks or hangers L² L². The shafts L L' are provided with any desired number of cog-wheels l. Two are shown on each shaft. 50 At their front ends the shafts L L' are provided with miter-wheels M M'. At the rear end of the shaft L is a cam-wheel, L², on which is placed an anti-friction roller, a, that is journaled on the horizontal bent upper end of a 55 wire rod, b, that slides vertically in guides c, and the lower end of which wire rod passes through an eye, I², that is formed in the end of an arm that extends from the bell-lever I'. 60

N designates the indicating-cylinder, which 55 in this instance has four faces, on each of which is printed or painted the name of one of the outer buildings surrounding the residence. The

indicating-cylinder N is provided on its ends with bevel gear-wheels N' N², which engage the miter-wheels M M' on the front ends of the 55 shafts L L', so that when either shaft is turned the indicating-cylinder N will be operated. The sides of the alarm-case A are provided with plates O, having rectangular openings O', through which the slides P P' P² P² pass. The 60 wires for operating the slides are connected to the slides and to the door of the building, and may be run under ground or on poles, as may be desired.

R represents rack-bars that are secured on 65 the under sides of the slides P P' P² P², and when the slides are drawn out mesh with the cog-wheels l, and to each of the slides is secured a stop, S, which, when the slide is drawn out, 70 strikes against the inner side of the box and prevents the slide from being drawn out farther. These stops are arranged on the slides 75 out of line with each other, as shown, so that no two of the slides can be moved the same distance. When the slide P is moved, it goes far enough to cause the indicating-cylinder N to make a quarter-revolution. The slide P' 80 can move far enough to cause the indicating-cylinder to make a half-revolution, the slide P² can move far enough to cause the indicating-cylinder to move three-quarters around, and the slide P² can move far enough to cause the 85 indicating-cylinder to rotate once. Each of the slides is connected by a wire to a door or window, and when said door or window is 90 opened the movement of the slide causes the indicating-cylinder to present its correspondingly-inscribed face to the opening in the case, the cam-wheel L² raises the wire rod b, so as to disengage the rod from the eye of the bell-lever, and the striking alarm mechanism is thereby set in operation, as will be very readily understood.

Having thus fully described my invention, what I claim as new, and desire to secure by 95 Letters Patent of the United States, is—

1. The combination of the inclosing-case having an opening in one of its sides with the revolving indicating-cylinder journaled in the case behind the opening, the shafts journaled in the case, having spur-wheels and gearing connecting said shafts with the revolving indicating-cylinder, and the slides having rack-bars that mesh with the spur-wheels on the 100

shafts, and stops for limiting the movement of the slides, substantially as described.

2. The combination of the inclosing-case having an opening in one of its sides with the revolving indicating-cylinder journaled in the case behind the opening, the shafts journaled in the case, having spur-wheels and gearing connecting said shafts with the revolving indicating-cylinder, the slides having rack-bars that mesh with the spur-wheels on the shafts, stops for limiting the movement of the shafts, the gong, the striking mechanism, and the trip-rod for releasing the striking mechanism, and the cam on one of the shafts for raising the rod, substantially as described.

3. The combination of the inclosing-case

with the gong, the striking mechanism having the bell-lever provided with an eye, the trip-rod which enters the eye of the bell-lever, the shaft journaled in the case, having spur-wheels, and the cam secured to the shaft for raising the trip-lever, and the slides having rack-bars meshing with the spur-wheels on the shaft, substantially as described.

In testimony that I claim the foregoing as my own I have hereto affixed my signature in presence of two witnesses.

FRANK CROSS.

Witnesses:

JAMES C. LAVELLE,
ALLEX CHIMEL.
